SIDNEY S. HURLBUT, OF CORDOVA, ILLINOIS.

Letters Patent No. 77,490, dated May 5, 1868.

IMPROVEMENT IN GRAIN-SEPARATOR

The Schedule referred to in these Letters Patent and making part of the same.

TO ALL WHOM IT MAY CONCERN:

Be it known that I, SIDNEY S. HURLBUT, of Cordova, in the county of Rock Island, and State of Illinois, have invented a new and improved Grain-Separator; and I do hereby declare that the following is a full, clear, and exact description thereof, reference being had to the accompanying drawings, making a part of this specification, in which—

Figure 1 is an elevation of one side of the machine.

Figure 2 is a top view.

Figure 3 is a section, taken longitudinally through the machine, in the vertical plane indicated by red line xx in fig. 2.

Figure 4 is a sectional view, in detail, of the grain-screens.

Similar letters of reference indicate corresponding parts in the several figures.

This invention relates to a new and useful improvement on fanning-mills or separators, whereby oats and other grains and foreign substances are separated from wheat by a repeated or successive passage of the unclean wheat through the screens, while that portion of the wheat which is cleaned or separated from its impurities is conducted out of the machine.

The nature of my invention consists in a grain-separating shoe or "huddle" of a peculiar construction, which is suspended in front of a fan, so as to receive a shaking movement, and, at the same time, strong blasts of air, in combination with an elevator, which is so arranged that all that portion of the wheat which is not cleaned or separated of its impurities after passing through the said huddle will be elevated and discharged into the hopper, to be again subjected to the cleaning-process, which operations will be repeated as long as the machine is in motion, as will be hereinafter described.

To enable others skilled in the art to understand my invention, I will describe its construction and operation.

In the accompanying drawings, A represents the frame of the machine, which is provided with a rotary fan, B, and a fan-case, C, at one end, and left open at its opposite end, for the escape of oats and other foreign substances blown off by the fan-blast. On top of this frame A is a hopper, D, and on one side of this frame A, outside, is an elevator-case, E. This elevator-case has a spout, E¹, emptying into the hopper D; and it contains an endless band of buckets, a a, which receive wheat, mixed with foreign substances, in a chamber, E², at its base, and discharge it into said hopper.

The shaft b of the upper drum, over which the band of buckets a passes, carries a small pulley, c, which is driven from a large pulley, c', on a short shaft, e, which pulley c' receives motion from the fan-shaft, through the medium of two spur-wheels, g g', thereby causing the buckets in the elevator-case to move around by the motion imparted to the upper drum from the fan-shaft.

The opposite end of the fan-shaft has a crank formed on it, which communicates motion to a right-angular lever, d, through the medium of a connecting-rod, d', as shown in fig. 2, which lever is connected to and imparts a rapid shaking motion to the grain-screens.

Within the frame A, and suspended from it by means of straps h h h, is a screen-shoe, G, having a number of sieves or screens arranged within it, as will be hereinafter described; and below this screen-shoe is a receiving-board, H, which inclines, as shown in fig. 3, and receives upon it the partially-cleaned wheat falling from the screens, and delivers this impure wheat into a trough, I, which inclines toward and delivers the wheat and its foreign matters into the chamber E² of the elevator-case, to be carried up and again discharged into the hopper D. Another screen, J, is arranged beneath some of the screening-surfaces of said shoe G, and partly over the inclined board H and trough I, for the purpose of receiving all the cleaned wheat, and discharging it into an inclined trunk, K, which carries it out of the machine beneath the fan-case, as shown in fig. 3.

I will now describe the construction and arrangement of the screens or sieves which effect the separation of the wheat from oats and other substances found mixed with it.

My object in arranging the screens in the shoe G, as shown in the drawings, figs. 3 and 4, is to allow the wheat which will readily pass off clean to escape first, and as quickly as possible, and then to conduct the wheat

mixed more or less with impurities over and through screening-surfaces subjected to strong and also rapid rotary motions, gathering these substances finally upon the inclined board H, to be conducted back to the hopper D, and passed through the several screens again. Another object of arranging the several screens as shown is to regulate the amount of screening-surface, according as there may be more or less impurities mixed with the wheat.

The first or highest screen L receives the wheat mixed with foreign grains and other substances from an inclined board, L', which is arranged beneath the feed-opening of the hopper D, which opening can be increased or diminished in size by the slide D'. Beneath this screen L is a short screen, p, and a long screen, p', which are arranged in the same inclined plane. The long screen is made movable, so that it can be drawn entirely out when the wheat is not very much mixed with foreign matters. Beneath these screens p, p' are two inclined screens, r, r', the shortest and highest one of which slightly overlaps the long one, so as not to allow the grains to be arrested at this point, but to cause it to pass off upon the screen r' as quick as possible.

Beneath the screen r' are two short screens, s, t, which will screen that portion of the grain that does not pass through the previously-mentioned overhanging screens p and r. The highest portion of the uppermost screen L and the two short screens p and r overhang or extend back of the two screens s, t, and all the clean wheat which escapes through these overhanging screens falls upon the screen J, and is immediately conducted off, as before described.

Beneath the lowermost short screen t is a narrow board, V, which is secured to the shoe by means of screws passing through oblong slots made through this board, for the purpose of adjusting the latter toward or from the upper end of the screen t. This board is designed to serve as a cut-off, for preventing impure wheat from falling upon the screen J, and being carried off with the pure wheat. Another cut-off, T, is applied over the short screen, r, so that it can be moved back and forth, for the purpose of covering up more or less of this short screen, as may be required.

It will be seen, from the above description, that the screens are so arranged that all the clean wheat which is allowed to escape through the heads or upper ends of the screens will be carried directly out of the machine, and will not pass over the other screen-surfaces with the impurities.

The cut-off T is designed for regulating the size of the short screen p, according as there may be more or less impurities mixed with the wheat, and the cut-off or gauge V is intended for separating the clean from the unclean grain in the fall of the same from the screen t, and for directing the unclean grain upon the inclined board H to be carried up to the hopper again for re-screening.

Having described my invention, what I claim as new, and desire to secure by Letters Patent, is—

1. The combination of the screening-shoe, constructed and operating substantially as described, with an elevator, which leads back into the hopper, and with a cleaned-grain discharge-passage, substantially as described and for the purpose set forth.
2. I claim the employment of an elevator, which will return that portion of the wheat which escapes from the screens in an unclean state back to the hopper to be re-screened, substantially as specified.
3. The combination of the screens L, p, and r', the short screens s, t, the cut-off T, and the gauge V, with means for conveying the clean wheat out of the machine, and also for conducting back to the first screen L the wheat, which is mixed with foreign substances, substantially as described.

SIDNEY S. HURLBUT.
